HENRY JAMES HICKEY, OF FORT DODGE, IOWA.

PISTON-VALVE.

1,174,722.

Specification of Letters Patent.

Patented Mar. 7, 1916.

Application filed March 11, 1915. Serial No. 13,725.

To all whom it may concern:

Be it known that I, HENRY JAMES HICKEY, a citizen of the United States, and a resident of Fort Dodge, in the county of Webster and State of Iowa, have invented a certain new and useful Improvement in Piston-Valves, of which the following is a specification.

My present invention relates generally to piston valves for steam, gas, and other engines, and more particularly to piston valves for internal combustion engines, my object being to provide an improved valve arrangement of this character whereby to decrease the noise and increase power over the usual puppet valves of the same bore and stroke, and one which will effectively operate without the formation of compression. These objects are realized, and the resulting advantages attained, by the piston valve shown in the accompanying drawing in connection with a V-type internal combustion engine, and in which drawing

Figure 1 is a vertical section; Fig. 2 is a side elevation of one of the piston valves; Fig. 3 is a detail sectional view taken through one of the piston valves and its bore substantially on line 3—3 of Fig. 1. Fig. 4 is a side elevation of the eccentric actuating 10 the piston valves and their pistons; Fig. 5 is a cross section taken through the piston of one of the valves, substantially on line 5—5 of Fig. 6; Fig. 6 is a detail view, partly broken away and in section, of the end of 15 one of the pistons; and Fig. 7 is a detail view through the expansion ring, taken substantially on line 7—7 of Fig. 5.

Referring now to these figures, it will be seen that each of the cylinders A in which is arranged a main piston B, is provided at one side with a cylindrical bore A', extending longitudinally thereof and slightly inclined with respect thereto, the cylinder A and its said bore A' communicating at one 20 end by a passageway a, substantially opposite the exhaust C and the inlet port, the latter not shown.

The bore A' accommodates a cylindrical piston valve D constructed in accordance 25 with my invention, and which, with the objects before mentioned in mind, is substantially hollow, with a squared axial opening d, and with a substantially tortuous 30 passage d', leading from the squared axial opening d, through one of the internal wrist pins d', so as to permit of its registration

with the relief port E which leads from the bore A' intermediate its ends.

It will be noted that the water jacket F of the cylinder may extend around the bore 60 A' as shown in Fig. 1, and it will be further noted from the right hand portion of this figure that the valve D in its outermost position, at the end of its stroke, covers the exhaust C, cutting off the same from the piston 65 cylinder A.

Extending through the squared opening axially of the piston valve D, is a squared piston G, the extremity of which is provided with a substantially axial opening g communicating at its inner end with a port g' laterally opening to one side thereof and adapted, when the piston G is at the innermost limit of its travel with respect to the piston valve D, to register with the tortuous 70 course d' before mentioned at a time when the outer end of the latter is registered with the relief port E.

The stem G' of the valve piston G extends 80 inwardly and is connected to the central offset H' of an eccentric H secured upon the eccentric shaft I which is connected by suitable gearing, in the present instance, sprocket wheels i and i' and a sprocket chain I', to the power shaft J, to which the pitmen B' 85 of the working pistons B are connected. Connecting rods G' similarly extend between offsets H' of the eccentric H, and the piston valve D, these connecting rods having outer ends extending into the piston valve and 90 loosely connected to the wrist pins d' before mentioned. Thus by means of the gearing between the power shaft J and the eccentric shaft I, coupled with the throw of the piston valves D and their pistons G, the timing of 95 the movement of the piston valves and their pistons with respect to the movement of the working pistons B, may be readily controlled. It will be noted, however, that the offset H' of the eccentric H is substantially 100 larger than the offset H', hence the stroke of the pistons G will be greater than that of the valves D in which they work. Thus the pistons G disposed within the valves D, are movable therewith within the bore J' and 105 are also movable with respect to the valves D so as to control the ports thereof, the valves D themselves controlling the inlet and outlet ports to the working cylinder.

To prevent leakage, the pistons G within 110 the piston valves D are each provided with recesses therearound, receiving the parts of

a rectangular packing composed of four parts such as shown in Fig. 5, the parts K of which are grooved at their ends to receive tenons on the ends of the parts K' as clearly seen by a comparison of Figs. 5 and 7.

In operation, the objection to the usual piston valve is that when the engine is running at a high engine speed and the valve 10 itself passes the ports, closing off either the intake or exhaust or both, it compresses the chamber to a smaller area, thus giving back pressure throughout the valve arrangement. With my construction, just as the valve 15 passes the intake and exhaust ports, the relief piston, Fig. 3, opens the passage through relief port E. The eccentric before described controlling the valve and its piston are so timed that when the valve has fully 20 closed the intake and exhaust ports, the relief piston holding open the passage through port E and having a longer travel, continues to move upward and closes the passage 25 through port E, when main piston B is making ready for an explosion. Thus, when piston B is at its outermost point and ready to fire, both the relief valve and its piston are 30 at their outermost point with all ports closed. The advantage of this type of valve is that it may travel at a high rate of speed without compression or back pressure after passing the intake and exhaust ports, thus taking all 35 strain from the valve.

A piston valve thus constructed and operating, will greatly decrease the noise in connection with an internal combustion engine, and will at the same time materially increase 40 the power as compared with that derived in connection with the usual puppet valve of the same bore and stroke. Furthermore, a piston valve constructed and operating as described, will obviate the necessity for all 45 rocker arms, puppets, valve springs, and the multitudinous cams usually incident to the valve construction of internal combustion engines.

In addition to the above, the particular construction of my improved piston valve enables the same to operate successfully and 50 without the formation of compression which is usually a drawback in this form of valve, particularly in connection with internal combustion engines.

I claim:

55 1. The combination with a cylinder, a side bore having fuel ports for the cylinder and one end of which opens into the cylinder, and a relief port leading from the said bore intermediate its ends; of a piston valve slidable 60 in the bore to cover and uncover the cylinder ports and having a body opening axially

thereof, and a port leading outwardly through its side from the said axial opening to register with the said relief port when the valve covers the cylinder ports, a piston working 65 in the opening of the valve and controlling its said port, and means for moving the piston valve and its piston in the bore and with respect to one another.

2. The combination with a cylinder, a side 70 bore having fuel ports for the cylinder and one end of which opens into the cylinder, and a relief port leading from the said bore intermediate its ends; of a piston valve slidable in the bore to cover and uncover the cylinder 75 ports and having a body opening axially thereof and a port leading outwardly through its side from the axial opening to register with the said relief port when the valve covers the cylinder ports, a piston working 80 in the opening of the valve and controlling its port, a shaft having geared connection with the power shaft, and an eccentric secured upon the first-mentioned shaft and having offsets respectively controlling the 85 movements of the valve and its piston, the piston controlling offset being substantially larger than the valve controlling offset, whereby to give the piston of the valve both movement with the valve in the bore and 90 with respect to the said valve in its axial opening.

3. The combination with a cylinder, a side bore having fuel ports for the cylinder and opening at one end thereinto, and a relief 95 port leading from the said bore intermediate its ends; of a ported piston valve operating in the bore to cover and uncover the said fuel ports, and a piston operating with the valve and controlling communication of its 100 port with the said relief port.

4. The combination with a cylinder, a side bore having fuel ports for the cylinder and opening at one end thereinto, and a relief port leading from the said bore intermediate 105 its ends; of a piston valve having ports and operating in the said bore to control the said fuel ports, a piston operating within the valve and controlling its ports, a driven shaft, and an eccentric secured on the said 110 shaft and connected to the said valve and its piston for controlling movement thereof, certain of the offsets of the said eccentric, connected to the piston, being substantially larger than the offset thereof connected to 115 the valve, whereby to increase the stroke of the piston with respect to that of the valve in which it works.

HENRY JAMES HICKEY.
